BURNER MECHANISM

Gray Coggin, Roswell, N. Mex.

Application January 31, 1947, Serial No. 725,419

4 Claims. (Cl. 126—271.2)

1

This invention relates to improvements in burner mechanisms, particularly of the character used for melting snow on highways and for burning brush, etc., along highways and in fields.

Various brush burners have been proposed heretofore, but these have not had universal application and adjustment and particularly have not been adaptable for the melting of snow along highways. Furthermore, they have not been efficient in operation nor capable of adjustment to the extent often required.

One of the objects of this invention is to improve the construction of burner mechanism so as to make this adaptable for the melting of snow along highways, for the burning of brush in fields and other places; and for various other burning actions wherever required.

Another object of the invention is to provide for an adjustment of the burning mechanism, to make this adaptable to various burning conditions, and to be vertically and angularly disposed with respect to the slope or crown of a road or a field where the burning action may be desired, and to obtain a more efficient burning action at the point required for melting snow, burning brush, etc., as well as providing for a folding or adjustment of the burner mechanism for travel along the highway or through relatively close space as desired for movement of the machine from place to place.

Still another object of the invention is to improve the construction of the burner provided in the mechanism to obtain efficient operation thereof and to provide for the burning of butane or other suitable gaseous fuel in an efficient and effective manner.

These objects may be accomplished, according to the embodiment of the invention, by mounting a burner or burners on a portable supporting device so these may be moved along to the point of use as desired, and providing for universal adjustment of the burner or burners both as to tilting action and also for bodily adjustment with respect to the slope of the surface where the burning is to be accomplished, the crown of the road, etc., and also, where a plurality of burners are provided extending laterally in opposite directions from the portable supporting device, providing for adjustment of these to parallel relation for transporting along the road or through a confined space.

An effective burner is provided by means of a burner tube into which a nozzle extends for supplying a mixture of gaseous fuel and air that are intermixed in the nozzle and injected into

the tube in such relation to the latter that additional air is taken in at the inlet end of the tube. The air is supplied to the nozzle for intermixing with the gaseous fuel under sufficient pressure to obtain an intimate mixture with the fuel so that an effective and efficient burning action is accomplished when this gaseous mixture containing air is injected into the burner tube.

An embodiment of the invention is illustrated in the accompanying drawings in which:

Fig. 1 is a side elevation of the invention;

Fig. 2 is a detail horizontal section through one of the hoisting units, showing the connection of the burner air tubes thereto, taken on the line 2—2 of Fig. 4;

Fig. 3 is a detail cross-section through the burners on the line 3—3 in Fig. 4;

Fig. 4 is a rear elevation of the burner mechanism;

Fig. 5 is a detail cross-section through the vaporizer on the line 5—5 in Fig. 4;

Fig. 6 is a sectional view at right angle thereto taken on the line 6—6 in Fig. 4;

Fig. 7 is a top plan view of the burner mechanism; and

Fig. 8 is a detail sectional view on the line 8—8 in Fig. 4.

The portable burning mechanism is adapted for transportation from place to place and along the surface where the burning action is to be accomplished. It is accordingly mounted on and supported by a conveyance, such as a trailer generally designated by the numeral 1, being of the character ordinarily used for attachment at the rear of a tractor, truck or other power vehicle for the hauling of various articles thereon. The trailer 1 is provided with a supporting frame 2 thereon having a depending step portion generally indicated at 3 located at the rear thereof.

The burners are supported from the frame-step portion 3, by means of hydraulic lifts or jacks generally indicated at 4. Each of the lifts 4 includes a piston 5 fixed at its lower end to the frame step portion 3 and in upstanding relation relative thereto. A cylinder 6 is slidably mounted upon the piston 5 for up and down movement relative thereto. The upper portion of each cylinder 6 includes a hydraulic chamber adapted to be supplied with liquid through a supply tube 7 that is flexible to accommodate for various adjustments of the cylinder 6.

The supply tube 7 extends to a 3-way valve 8, one side of which is connected at 9 to a hydraulic pump 10, while the other side thereof is connected at 11 to a liquid reservoir 12. The

pump 10 is power driven by an engine 13. Thus upon turning of the valve 8 to either of its positions, liquid will be pumped from the reservoir 12 by means of the pump 10 through the tube 7 into the chamber of the cylinder 6, or the liquid will bleed from the chamber in the cylinder 6 through the tube 7 and the valve 8, directly into the reservoir 12 through the connection 11, this bleeding being accomplished by gravity acting on the burners supported on the cylinder 6, as hereinafter described.

The burners are shown as supported by a series of pipes extending outwardly in opposite directions from the respective hydraulic lifts 4, three pipes being shown on each side of the conveyance as indicated at 14 and 15. However, any suitable number of pipes may be used according to the number of burners desired for the mechanism. The pipes 14 and 15 are held in parallel spaced relation by transverse bars 16 and 17 located respectively at the inner and outer ends of the pipes 14 and 15. The pipes 14 and 15 are journaled in the bars 16 and 17, capable of rotation relative thereto, but are adapted to be locked in adjusted positions by means of set screws 18.

Each of the pipes 14 and 15 is closed at its outer end, while the inner ends thereof are connected with air supply ducts 19 leading to a blower 20 driven by the engine 13, as shown in Fig. 7, whereby air will be supplied under pressure to the respective air pipes 14 and 15. The burner assemblies, one on each side of the trailer, are adapted to be supported by the hydraulic lifts 4. As shown, the inner end of each burner assembly is mounted on the lift 4 in the manner illustrated in Figs. 2 and 4. The pipe 14 is extended and connected by a swivel 21 and a pivot 22 to a lug 23 welded or otherwise rigidly fixed to a side of the cylinder 6. The swivel 21 comprises a plate secured to the end of pipe 14 and rotatable therewith and said plate is positioned within a socket in said swivel with a retaining ring threadably retaining said plate against outward movement. This swivel arrangement will permit the plate mounted on the pipe to rotate within the socket of swivel 21. A set screw for engagement with the plate on the end of pipe 14 is provided to hold the pipe in adjusted position. This will allow both for rotation or turning movement of the pipe 14 to accommodate a tilting action of the burners as indicated by dot-dash lines in Fig. 1, and also for swinging movement about pivot 22 of the entire burner assembly to accommodate for irregularities or variations in slope of the surface of the road or field on which the burner mechanism may be operated, as is often desired.

The lug 23 is bifurcated at 23a to form outstanding lugs, as will best be seen in Fig. 2, to receive a complementary lug 21a formed on the inner end of socket swivel 21. A set screw 21b threadably engages socket swivel 21 and projects therethrough to interengage the plate 14a welded or otherwise secured to the inner end of tubular support member 14. A threaded bushing 21c surrounds tubular support means 14 and threadably interengages the swivel socket 21 so as to hold tubular members 14 and 15 in fixed relation with respect to hydraulic cylinder 6, when set screw 21b is secured in place.

The outer end of each burner assembly is supported by a lug 24 connected with the outer end of the pipe 14, and a flexible device 25 that extends from the lug 24 to a hook 26 attached to the upper end of the cylinder 6. This flexible device 25 is shown as including a section of chain,

the length of which may be adjustably connected with the hook 26 to vary the length of the flexible device, thereby to raise or lower the outer end of the burner assembly.

In the form illustrated, each of the burner assemblies includes a multiplicity of burners adapted for burning gaseous fuels, such as butane, propane, or other form of liquefied gas, although other types of gaseous fuels may be used if desired. In the form illustrated in Figs. 3 and 6, each burner includes a burner tube 27. The burner tube 27 is open at opposite ends, and is mounted in an upright position so as to receive air in the upper end thereof and to direct the flame from the burner in a downward direction, according to the angle of the burner tube as illustrated in full lines and in dotted lines in Fig. 1. Each burner tube 27 is provided preferably with a jointless fire-clay lining 28, introduced therein under pressure and baked.

The burner tubes 27 are mounted in pairs along one side of each pipe 14 and 15 as shown more clearly in Figs. 4 and 7. Each pair of burner tubes 27 is supported by a connecting pipe 29 that extends therebetween as shown in Fig. 6 and coacts with an outlet pipe 30 to form a T. The outlet pipe 30 is in open communication at its lower end with the connecting pipe 29, and at its upper end has tubes 31 leading therefrom to nozzles 32.

Each nozzle 32 discharges into a mixing chamber 33 in open communication with one side of the air supply pipe 14 or 15, for intimate mixture of the gaseous fuel and the air within the mixing chamber, which mixture then is injected into the burner tube 27 through a nozzle 34 which is disposed approximately axially of the burner tube and in position spaced from the surrounding sides thereof to allow freedom for admission of air through the adjacent end of the burner tube from the surrounding atmosphere. The T formed by the connecting pipe 29 and the outlet pipe 30 acts as a vaporizer for any liquefied fuel that reaches the connecting pipe 29, absorbing heat for vaporization from the burner tubes 27 in heat exchange relation with the connecting pipe 29 when the burners are in operation.

Fuel is supplied to the burners through a branch pipe 35 having a notch 36 in the lower end thereof, and which branch pipe extends downward through the outlet pipe 30 to the bottom of the connecting pipe 29 as shown in Figs. 5 and 6. The upper end of the branch pipe 35 is joined to a fuel supply pipe generally indicated at 37, which pipe 37 extends along the series of burners and to a fuel tank 38 shown in Figs. 1 and 7.

The fuel supply pipe 37 is connected with a tube 39 that receives fuel from the tank 38. The tube 39 may open into the top of the tank 38 and thereby withdraw vaporized gas from the top of the tank or it may form a dip tube extending to the bottom of the tank for the withdrawal of liquefied fuel from the tank which, in turn, is vaporized in the connecting pipe 29 when the burners are in operation. Where vaporized fuel is withdrawn from the top of the tank 38, any liquid particles contained therein will be vaporized or re-vaporized in the vaporizer formed by the connecting pipe 29 in heat-exchange relation with the burners 27.

In the operation of the burner mechanism, the burners are first adjusted in position according to the character of the work to be performed, that is to say, whether the burner mechanism

is to be used for melting snow and ice along a highway or for burning brush in a field or along a highway, it being preferred to direct the flame downward from the burners in vertical positions as shown in full lines in Fig. 1 where the mechanism is used for melting snow and ice, or to tilt the burners to an angular position as shown by dotted lines in Fig. 1 when burning brush. This latter adjustment may be accomplished where desired by loosening the set screws 18 and turning the pipes 14 and 15 to angular positions of the burners as shown, after which the set screws 18 may be tightened again to hold the pipes in their adjusted positions.

Furthermore, the burner assemblies may be tilted lengthwise if desired to accommodate for the slope of the surface over which the burner mechanism is adapted to travel, as for instance the crown of a road, when melting snow and ice therefrom. The latter adjustment may be accomplished by lightening or loosening the flexible devices 25 that support the outer ends of the burner assemblies, the universal connection 21-22 compensating for such adjustment. Furthermore the burner assemblies may be adjusted bodily up and down with respect to the surface of the road or field by the hydraulic lifts 4, to position the burners at the proper height relative thereto.

Then the burners may be operated to provide the desired heating or burning action. Fuel will be supplied from the tank 38 through the conduit 37 to the respective burners, discharging from the conduit 37 into the branch pipe 35, thence into the connecting pipes 29 from which vaporized fuel will be led off through the outlet pipe 30 and tubes 31 to the nozzles 32 that discharge this vaporized gaseous fuel into the mixing chambers 33. At the same time the blower 30 will supply air under pressure through the air ducts 19 to the respective pipes 14 and 15, thence into the mixing chamber 33 of the respective burners. This air is under pressure and will produce an intimate mixture with the gaseous fuel injected into the mixing chamber by the nozzle 32, whereby an efficient combustion is produced when the mixture is discharged through the nozzle 34 into the burner tubes 27. Any additional air needed to support combustion will be drawn in at the open upper end of the burner tube 27. A high degree of efficiency is obtained thereby and a very hot flame results when discharged from the lower end of the burner tube downward toward the road surface or field where burning or heating may be desired.

With the burners thus operating, the entire burner mechanism may be drawn along the road surface or field by attachment of the trailer 1 to a tractor, truck or other conveyance, moving the burner mechanism over the surface where the heating or burning action is desired. After thus accomplishing the desired heating or burning action, the burner mechanism may be moved by the trailer 1 to another point where such action is required or to a point of storage. This transporting may be accomplished effectively on the trailer, and to facilitate the movement along a highway, the burner assembly may be moved around to parallel relation, substantially as indicated by dotted lines in Fig. 7. Such parallel relation may be possible, especially when the burner assemblies are relatively wide, by raising one of the assemblies to a position above the other, as indicated in dotted lines in Fig. 4, which is accomplished by a lifting action of the corre-

sponding hydraulic lift 4. Then when further use is desired, it is a simple matter to restore the parts to the position indicated in the drawings, ready for operation.

This mechanism is capable of wide variations as to adjustment to meet the different operating conditions or to accommodate itself to different types of heating or burning actions and different angles of slope or crown of a road, airfield runway, embankment or ditch where such actions may be desired. It is extremely effective in operation, particularly for removing snow or ice from a highway or airfield runway strip by vaporization of the ice or snow, or for burning brush and weeds from a field or along a highway, embankment or side of a ditch. It is highly efficient in operation, producing a very hot flame from the multiplicity of burners, that accomplishes the desired results.

While the invention has been illustrated and described in one embodiment, it is recognized that variations and changes may be made therein without departing from the invention except as specified in the claims.

I claim:

1. In a portable device for performing a burning action a wheeled carriage, a hydraulically operated vertical support member mounted on said wheeled carriage, a plurality of spaced parallel support bars mounted on said hydraulically operated vertical support member, one of said parallel support bars being journaled for rotary and pivotal movement with respect to said hydraulically operated vertical support member so as to obtain various angular adjustments of said parallel bars with respect to the terrain over which the device operates, a plurality of burners mounted in spaced transverse and longitudinal relation on said parallel support bars rearward of said wheeled carriage, a plurality of transverse bars journaling said parallel support bars for arcuate movement, means for securing said parallel support bars in adjusted relation to said transverse bars so as to hold the burners in an angular adjusted relation with respect to the terrain over which the device operates, and a flexible device extending between the outer end of one of said parallel support bars and the upper end of said vertical support member for varying the angularity of said parallel support bars with respect to the terrain over which the portable device operates.

2. A portable burning mechanism comprising a wheeled conveyance, an elongated burner assembly including a plurality of elongated tubular supporting means extending laterally from said wheeled conveyance, a plurality of transverse bars connected with said tubular support means for holding said tubular supporting means in substantially parallel spaced relation, a plurality of burners carried by said tubular supporting means and spaced lengthwise therealong, means mounting said tubular supporting means on said wheeled conveyance including a vertical hydraulic lift device and universal connecting means between said tubular supporting means and said hydraulic lift device to provide freedom of angular adjustment of said tubular supporting means relative to said hydraulic lift device and to provide for bodily adjustment of said tubular supporting means by said hydraulic lift device to different elevated positions.

3. A portable burning mechanism comprising a wheeled conveyance, an elongated burner assembly including a plurality of tubular support

ing means extending laterally from said wheeled conveyance, transverse bars journaling said tubular supporting means and holding said tubular supporting means in substantially parallel spaced relation but permitting selective turning movement thereof with respect to said transverse bars, means for optionally securing said tubular supporting means against turning movement relative to said transverse bars, a plurality of burners carried by said tubular supporting means and spaced lengthwise thereof, means mounting said plurality of burners on said wheeled conveyance including a universal connection at one end of said tubular supporting means, a vertical hydraulic lift device mounted on said wheeled conveyance and supporting said universal connection, and a flexible device extending from said hydraulic lift device to the opposite end portion of said tubular supporting means for the support thereof.

4. In a burner mechanism comprising a wheeled conveyance, a pair of substantially vertical hydraulic cylinders mounted on upwardly extending hydraulic plungers at the rear of said wheeled conveyance, each of said cylinders being sleeved over said respective plungers for sliding movement thereon and for pivotal movement thereabout, a pair of laterally spaced outstanding lugs secured near the lower end of each of said cylinders, a complementary lug interfitted between each pair of said outstanding lugs, each of said complementary lugs and each of said outstanding lugs having an aperture formed therethrough, a pivot pin fitted within said apertures and pivotally mounting said lugs for movement in a vertical plane with respect to each other, each of said complementary lugs having a swivel member secured thereto each of which swivel members has a socket therein, a plate rotatably positioned within each of said sockets for relative turning

movement with respect to said sockets, a screw member threadably engaging said respective sockets for bindingly engaging each of said rotatable plates in said respective sockets to secure same against relative turning movement, each of said rotatable plates carrying a plurality of outwardly extending tubular support means and each tubular support means carrying a plurality of burners spaced therealong for directing a flame substantially downward, means for supplying fuel to said burners, and means for raising said hydraulic cylinders and said burners.
